Primary Examiner — Susan Bennett Hattan*Assistant Examiner* — Marie Fast Horse(74) *Attorney, Agent, or Firm* — McGarry Bair PC(57) **CLAIM**

The ornamental design for a ceiling fan blade, as shown and described.

DESCRIPTION

FIG. 1 is a top perspective view of a ceiling fan having a ceiling fan blade according to the invention;

FIG. 2 is a bottom perspective view of the ceiling fan blade of FIG. 1;

FIG. 3 is a side view of the ceiling fan blade of FIG. 1;

FIG. 4 is a side view of the ceiling fan blade of FIG. 1;

FIG. 5 is a top view of the ceiling fan blade of FIG. 1; and,

FIG. 6 is a bottom view of the ceiling fan blade of FIG. 1. Portions of the ceiling fan shown in broken lines depict environmental subject matter only and form no part of the claimed design.

1 Claim, 5 Drawing Sheets(56)
